ABSTRACT

A hook bar for a multiple needle-tufting machine having alternating staggered slots in the front and rear faces of the hook bar for receiving loopers in a narrow gauge.

NARROW GAUGE HOOK BAR FOR TUFTING MACHINE

BACKGROUND OF THE INVENTION

This invention relates to a multiple needle-tufting machine, and more particularly to a hook bar for a multiple needle-tufting machine.

Conventional hook bars for multiple needle-tufting machines are long bars extending transversely of the machine below the needles and the base fabric. A conventional hook bar has uniformly spaced slots in its rear face for receiving the loopers which cooperate with the needles to form loops in the yarns carried by the needles. For a narrow gauge multiple needle-tufting machine, the slots in the rear face of the hook bar must be formed close together.

Although the theoretical limit of the narrowness of the gauge is the thickness of the needles and the loopers, as a practical matter, the narrowness of the gauge is limited by the thickness of the walls in the hook bar between the looper slots. As the looper slots are spaced closer together, the walls between them become thinner, and therefore weaker. Furthermore, the walls between the looper slots must be thick enough to support the internally threaded holes formed through the rear face for supporting the screws which retain the loopers in the slots.

In order to form more narrow gauge tufting machines, needles have been arranged in staggered front and rear rows. A typical example of a narrow gauge multiple needle-tufting machine is disclosed in U.S. Pat. No. 2,976,829 of Roy T. Card, issued Mar. 28, 1961. The Card patent discloses staggered needles and a hook bar having looper slots formed in the rear face to receive loopers with alternately staggered hook bills so that each hook bill will cooperate with an alternately staggered needle.

SUMMARY OF THE INVENTION

It is therefore an object of this invention to provide a hook bar particularly constructed to receive loopers in a fore-and-aft staggered arrangement which will cooperate with staggered needles on a narrow gauge, and which will overcome the above enumerated disadvantages of conventional hook bars.

More particularly, the hook bar made in accordance with this invention has a rear row of transversely spaced looper slots formed in the rear face of the hook bar and a front row of transversely spaced looper slots formed in the front face of the hook bar. The front and rear slots are preferably equally spaced and staggered so that the loopers are arranged at the same uniform gauge as their cooperating needles.

By providing slots in both the front and rear faces, walls between each pair of slots may be twice as thick, for the same uniform gauge, as the walls between slots in the rear face of a conventional hook bar.

BRIEF DESCRIPTION OF THE DRAWINGS

FIG. 1 is a fragmentary, sectional elevation taken longitudinally through a multiple needle-tufting machine having a hook bar made in accordance with this invention, and disclosing the needles and loopers in operative loop-forming positions;

FIG. 2 is a fragmentary rear elevation of the hook bar and loopers disclosed in FIG. 1; and

FIG. 3 is a fragmentary top plan view of the hook bar with the loopers removed, taken along the line 3-3 of FIG. 1.

DESCRIPTION OF THE PREFERRED EMBODIMENT

Referring now to the drawings in more detail, FIG. 1 discloses a transverse needle bar 10 in a conventional multiple needle-tufting machine supporting a first row of front uniformly spaced needles 11 and a second row of uniformly spaced rear needles 12 offset preferably midway between the front needles 11, to provide a uniform needle gauge. The needle bar 10 is vertically reciprocated by conventional means, not shown, to cause the front and rear needles 11 and 12 to

move between an upper position above the base fabric 13 to a lower position penetrating the base fabric 13 so that the needles will carry yarns, such as yarn 14, through the base fabric 13 to form loops of tufting therein. The base fabric 13 is supported upon a needle plate 15 for movement, by means not shown, in the direction of the arrow of FIG. 1, that is, longitudinally from front to rear through the machine.

Cooperating with each front needle 11 for forming loops in the yarn 14 is a front looper 17. Also adapted to cooperate with each rear needle 12 to form a loop in a yarn carried by the needle 12 is a rear looper 18. The front looper 17 has a shank 19 of uniform thickness, and the rear looper 18 has a shank 20 of uniform thickness, and preferably of the same thickness as the shank 19.

All of the front loopers 17 and the rear loopers 18 are carried in the hook bar 22 made in accordance with this invention, and adapted to be reciprocated by conventional means, not shown, longitudinally from front to rear. FIG. 1 discloses the hook bar 22 and the loopers 17 and 18 in their rearmost operative positions for forming the loops with the needles 11 and 12 in their lowermost positions.

Formed in the front face 23 of the hook bar 22 are a plurality of uniformly spaced front slots 24 of uniform thickness, each front slot 24 having a thickness only slightly greater than the thickness of the shank 19 of the front looper 17. Each front slot 24 opens through the front face 23 and is adapted to receive the shank 19 of each front looper 17.

In a similar manner, a plurality of uniformly spaced rear slots 25 are formed through the rear face 26 of the hook bar 22. Each rear slot 25 is of uniform thickness, and only of slightly greater thickness than the thickness of the shank 20 of each rear looper 18. The rear slots 25 also preferably open through the rear face 26 of the hook bar 22 for receiving the shanks 20 of each corresponding rear looper 18.

In order to set the front loopers 17 and 18 on the same uniform gauge as the staggered needles 11 and 12, the rear slots 25 are staggered with relation to the front slots 24 so that each rear slot 25 is located longitudinally midway between a pair of front slots 24.

Each looper 17 and 18 is retained in its respective front slot 24 and rear slot 25 by means of the conventional looper retaining screws 28.

FIG. 2 clearly shows how the diameter of each screw 28 exceeds the width of each slot 25, and therefore limits the thickness of the walls between the slots 25 in the hook bar 22, as well as the walls between the slots 24.

The extra wall thickness between the slots 24 and slots 25 obtained in hook bar 22 is also important because, in a conventional hook bar, the walls between the looper slots in a narrow gauge machine can become so thin that they become flexible. When the slot walls become too flexible, the loopers become unstable and cannot be rigidly confined to the uniform needle gauge. Furthermore, flexible slot walls promote vibration of the loopers and unnecessary wear against the needles.

What is claimed is:

1. In a multiple needle-tufting machine having a plurality of needles disposed transversely across the machine and adapted to reciprocate and carry yarn through a base fabric moving in a plane longitudinally through the machine, a looper mechanism comprising:

- a. a hook bar mounted transversely below the plane of the base fabric for longitudinal reciprocable movement to an operative position below said needles,
- b. said hook bar having a front face and a rear face,
- c. transversely spaced front slots in said front face for receiving front loopers, so that each front looper will form a loop in a yarn carried by a first needle in said operative position,
- d. transversely spaced rear slots in said rear face for receiving rear loopers, so that each rear looper will form in operative position a loop in a yarn carried by a second needle.

2. The invention according to claim 1 in which said first needles are arranged in a front transverse row and said second needles are arranged in a rear transverse row.

3. The invention according to claim 2 in which said first needles are equally spaced and said second needles are equally spaced, each second needle being staggered midway between a pair of adjacent first needles, to form a uniform gauge, said front slots being equally spaced in said front face, and said rear slots being equally spaced in said rear face, each

rear slot being staggered midway between a pair of front slots, so that said front and rear slots are arranged in the same uniform gauge as said needles.

5 4. The invention according to claim 2 in which said front slots are of uniform thickness and open through the front face of said hook bar, and said rear slots are of uniform thickness and open through the rear face of said hook bar.
